SPOON OR SIMILAR ARTICLE

Leonard G. Ressegger, Sr., Oneida, N. Y., assignor to
Oneida Ltd., Oneida, N. Y., a corporation of New
York

Application October 2, 1956, Serial No. 43,189

Term of patent 14 years

(Cl. D54—12)

FIG. 1.

FIG. 5.

FIG. 2.

FIG. 3.

FIG. 4.

Fig. 1 is a front elevational view of a spoon showing my new design;

Fig. 2 is a rear elevational view;

Figs. 3 and 4 are sections on the respective lines 3—3 and 4—4 of Fig. 1; and

Fig. 5 is a side elevational view.

The essential features of my design for a spoon or similar article reside in the configuration of the handle in combination with the particular type of ornamentation as applied thereto.

I claim:

The ornamental design for a spoon or similar article, substantially as shown and described.
